US0D1049794S

(12) **United States Design Patent** (10) **Patent No.:** **US D1,049,794 S**
(45) **Date of Patent:** **** Nov. 5, 2024**

(54) **LUNCH BOX**

(71) Applicant: **DONGGUAN OUMENG
HOUSEWARE PRODUCTS CO.,
LTD, Dongguan (CN)**

(72) Inventor: **Jingsheng Xu, Yueyang (CN)**

(73) Assignee: **DONGGUAN OUMENG
HOUSEWARE PRODUCTS CO.,
LTD, Dongguan (CN)**

(**) Term: **15 Years**

(21) Appl. No.: **29/953,915**

(22) Filed: **Jul. 24, 2024**

(51) LOC (14) Cl. **09-07**

(57) **CLAIM**

The ornamental design for a lunch box as shown and described.

DESCRIPTION

FIG. 1 is a perspective view of a lunch box showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the lunch box that form no part of the claimed design.

1 Claim, 8 Drawing Sheets
